UNITED STATES PATENT OFFICE

CARL H. HOFFSTETTER AND ROBERT F. HOFFSTETTER, OF ERIE, PENNSYLVANIA

DESIGN FOR A STOVE TOP

Application filed June 9, 1931. Serial No. 40,146. Term of patent 14 years.

To all whom it may concern:

Be it known that we, CARL H. HOFFSTETTER and ROBERT F. HOFFSTETTER, citizens of the United States, residing at Erie, in the county of Erie and State of Pennsylvania, have invented a new, original, and ornamental Design for a Stove Top, of which the following is a specification, reference being had to the accompanying drawings, forming a part thereof, wherein—

Fig. 1 shows a perspective view of a stove top with all the grids exposed showing our new design;

Fig. 2 a similar view with one grid closed;
Fig. 3 a similar view with both grids closed;

Fig. 4 a plan view of the top with the parts as in Fig. 1;

Fig. 5 an end elevation of the top with the parts as in Fig. 1.

We claim:

The ornamental design for a stove top as shown and described.

CARL H. HOFFSTETTER.
